[57] CLAIM

The ornamental design for a motorcycle trailer hitch support, as shown and described.

DESCRIPTION

FIG. 1 is a side elevation view of the motorcycle trailer hitch support, showing my new design;

FIG. 2, a top plan view thereof;

FIG. 3, a bottom plan view thereof;

FIG. 4, an end elevation view taken from the hitch bracket end thereof; and

FIG. 5, an end elevation view taken from the mounting bracket end thereof.

FIG. 1

FIG. 2

FIG. 3

FIG. 4

FIG. 5
